Attorneys

UNITED STATES PATENT OFFICE.

GUSTAF L. FISK, OF HARRISBURG, PENNSYLVANIA.

RAILROAD-TIE.

1,358,536.

Specification of Letters Patent.

Patented Nov. 9, 1920.

Application filed December 20, 1919. Serial No. 346,314.

To all whom it may concern:

Be it known that I, GUSTAF L. FISK, a subject of the King of Sweden, and resident of Harrisburg, in the county of Dauphin 5 and State of Pennsylvania, have invented a new and useful Improvement in Railroad-Ties; and I do hereby declare the following to be a full, clear, and exact description thereof.

10 My invention relates to a metallic railroad tie.

The object of my invention is to provide a metallic tie of great strength and durability which may be readily rolled to shape, and of 15 such design as to give large and effective bearing surface between the tie and roadbed thereby lowering the maintenance cost, as well as a tie having other advantages, all as more fully hereinafter set forth.

20 In the accompanying drawing, Figure 1 is a side view of my improved tie; Fig. 2 is a plan view of same showing portions of the track rails arranged thereon; Fig. 3 is an enlarged section on the line 3—3, Fig. 2; 25 and Fig. 4 shows a modified form of my invention.

My improved tie consists of the bottom or bearing surface 2 with the sides 3 extending upwardly and diverging to form a substantially flaring trough section, and said tie may be rolled in suitable rolls and is preferably made of steel. The bottom of the tie is made broad to furnish a large bearing area where the track ballast is most 35 solid, while the taper of the sides will tend to wedge the tie into proper bearing on the ballast.

At the tops of the sides 3 are the outwardly extending flanges 4 with the downwardly extending lip portions 5 extending slightly outwardly. This construction forms the inverted U-shaped portions at the top of the sides of the tie which act to retain the ballast and form a firm support for 40 the entire tie while the downwardly extending lips 5 which extend only to a comparatively small depth will make re-ballasting easy and effective.

The flanges 4 are connected by the plates 50 6 which may be secured by the rivets 7 or other suitable fastening means to said flanges. These plates act to reinforce the tie and also serve as tie-plates for the support of the track-rails. These plates are secured to the flanges 4 a suitable distance 55 from either track rail 8 at points where the

bending moment on the tie section is greatly reduced.

In this way the tie is relieved of unnecessary strains which prevent the breaking or 60 cracking of the tie at the bolt or rivet holes connecting the plates with the tie.

The tie-plates 6 not only serve to protect the tie from undue strains and eliminate wear of the track-rails on the tie, but they 65 also strengthen the tie and furnish a large bearing area for the support of the track-rails.

These tie-plates are preferably made of "rolled section" design, and I have illustrated a rail fastening device for securing the rails in position on the ties, which rail fastening device forms the subject of a separate application for Letters Patent of the United States filed by me of even date here- 70 with, Serial No. 346,313, although it is apparent that any suitable form of rail fastening device may be employed in connection with my improved tie. 75

In Fig. 4 I have illustrated my invention 80 in connection with insulation for electric signals or other purposes. In this case insulating pads 10 are inserted between the tie-plates and the tie proper, and bolts 11 with insulating bushings 12 and insulating 85 washers 13 are employed.

The chief advantages of my improved tie construction may be summarized as follows:

Low manufacturing cost due to the use of 90 rolled sections.

Simplicity and saving in manufacture, storage and installation by using the same tie construction for straight and curved 95 tracks.

Great strength and durability due to high section modulus per pound weight and due to the indirect fastening of the rails to the tie proper.

Proper flexibility due to shape of tie section which permits the tie to yield slightly under load.

What I claim is:

1. A railroad tie comprising a flat bottom portion with upwardly extending sides, 105 outwardly extending flanges at the tops of said sides, and downwardly extending portions on said flanges terminating at points spaced from said sides.

2. A railroad tie comprising a flat bot- 110 tom portion with upwardly extending di- verging sides, outwardly extending flanges

at the tops of said sides, and downwardly extending portions on said flanges terminating at points spaced from said sides.

3. A railroad tie comprising a flat bottom portion with upwardly extending sides, outwardly extending flanges at the tops of said sides and downwardly and outwardly extending portions on said flanges.

4. A railroad tie comprising a bottom portion, upwardly extending diverging sides,

outwardly extending flanges at the top of said sides and downwardly and outwardly extending portions on said flanges.

In testimony whereof I, the said GUSTAF L. FISK, have hereunto set my hand.

GUSTAF L. FISK.
